CLAIM

The ornamental design for a pouch for earbud charging case, as shown and described.

DESCRIPTION

FIG. 1 is a front perspective view of a first embodiment of a pouch for earbud charging case;

FIG. 2 is a front elevational view thereof;

FIG. 3 is a rear elevational view thereof;

FIG. 4 is a top view thereof;

FIG. 5 is a bottom view thereof;

FIG. 6 is a right side elevational view thereof;

FIG. 7 is a left side elevational view thereof;

FIG. 8 is a front perspective view showing the first embodiment of the pouch open;

FIG. 9 is a front perspective view of a second embodiment of a pouch for earbud charging case;

FIG. 10 is a front elevational view thereof;

FIG. 11 is a rear elevational view thereof;

FIG. 12 is a top view thereof;

FIG. 13 is a bottom view thereof;

FIG. 14 is a right side elevational view thereof;

FIG. 15 is a left side elevational view thereof; and,

FIG. 16 is a front perspective view showing the second embodiment of the pouch open.

The broken lines shown in FIGS. 8 and 16 are included for the purpose of illustrating an earbud charging case and forms no part of the claimed design.
